UNITED STATES PATENT OFFICE.

EUGENE CHAREST, OF DETROIT, MICHIGAN.

DESIGN FOR A TOY SAVINGS-BANK.

SPECIFICATION forming part of Design No. 22,419, dated May 9, 1893.

Application filed January 9, 1893. Serial No. 457,859. Term of patent 3½ years.

To all whom it may concern:

Be it known that I, EUGENE CHAREST, a citizen of the United States, residing at Detroit, county of Wayne, State of Michigan, 5 have invented a certain new and useful Design for a Toy Savings-Bank; and I declare the following to be a full, clear, and exact description of the same, such as will enable others skilled in the art to which it pertains to 10 make and use the same, reference being had to the accompanying drawing, which forms a part of this specification, and shows in perspective a toy bank made after my design.

In the drawing, appear the front, the top 15 and one side of the bank; the two sides which are not seen resemble the side which is shown except that the medallion heads differ from the one, which appears on the side shown. The bank consists of a cubical box of which 20 the lower or bottom side is left flat and plane; on each of the five remaining sides there is a hemispherical or nearly hemispherical boss. At the front is the door, and this is provided

at its middle or polar part with the knob, and surrounding the knob are concentric panels 25 for a suitable inscription. The boss at each side and that on the back are finished with an ornamental framework surrounding a medallion head. I employ as the heads used a representation of the head of Columbus, and 30 that of some officer of the Columbian Exposition. The hemisphere on the top of the bank is divided by lines into portions representing land and water, and represents one half of the terrestrial globe. Along the line bounding each side and in the corners where these lines meet are stars.

What I claim is—

The design for a toy savings bank as herein shown and described.

In testimony whereof I sign this specification in the presence of two witnesses.

EUGENE CHAREST.
